UNITED STATES PATENT OFFICE.

FRED W. DAFOE, OF ROCK ISLAND, ILLINOIS.

BOTTLING DEVICE.

No. 926,550.

Specification of Letters Patent.

Patented June 29, 1909.

Application filed December 12, 1908. Serial No. 467,258.

To all whom it may concern:

Be it known that I, FRED W. DAFOE, a citizen of the United States, residing at Rock Island, in the county of Rock Island and State of Illinois, have invented a new and useful Bottling Device, of which the following is a specification.

The improved bottling device herein described is of that general type which is adapted to be used in connection with bar spigots for the filling of bottles.

The objects of the invention are, generally, the provision, in a merchantable form, of a device of the above mentioned class which shall be inexpensive to manufacture, facile in operation, and devoid of complicated parts; specifically, the provision of an attaching member of novel and improved construction, of novel means for connecting the attaching member to a spigot, and of novel means for receiving the neck of a bottle during the process of filling; other and further objects being made manifest as the description of the invention progresses.

The invention consists in the novel construction and arrangement of parts, herein-after fully described, delineated in the accompanying drawings, and particularly pointed out in the appended claim, it being understood that divers changes in the form, proportion, size, and minor details of the structure may be made without departing from the spirit or sacrificing any of the advantages of the invention.

Similar numerals of reference are employed to denote corresponding parts throughout the several figures of the drawings.

In the accompanying drawings:—Figure 1 shows my invention in front elevation mounted upon a spigot; Fig. 2 shows my invention in longitudinal section, the same being mounted upon a spigot as in Fig. 1; Fig. 3 is a top plan of my invention.

In the accompanying drawings I have shown an ordinary spigot and designated the same generally by the numeral 1.

My invention comprises an attaching member denoted generally by the numeral 3 in Fig. 1, the said attaching member in its turn comprising a tubular body 2 exteriorly threaded at its upper terminal. Mounted upon the upper terminal of the member 2 is a resilient annular gasket 7 arranged to receive the end of the spigot. I further pro-

vide a clamping ring 6 internally threaded to engage the upper terminal of the member 2 and provided with an inwardly projecting shoulder 14 arranged to engage the gasket 7 and to hold the same firmly upon the member 2 when the clamping ring 6 is rotated. The member 2 terminates anteriorly in a reduced neck 8 which is bent laterally out of the axis of the member 2. The reduced neck 8 is provided with an axial bore 9 interiorly threaded at its lower terminal. From the lower end of the reduced neck 8 projects outwardly a flange 10. A discharge tube 4 is shown having its upper terminal threaded to engage the lower terminal of the reduced neck 8. A resilient packing surrounds the discharge tube 4 and this packing, in its preferred form, comprises a resilient washer 11 having plane faces arranged to abut against the flange 10, and surrounding the discharge tube 4. A second washer 12 is shown surrounding the discharge tube 4 and provided with a plane face in abutment with the washer 11. From the outer face of the washer 12 projects an annular rib 13 disposed in close relation to the discharge tube 4 and of less diameter than the member 12, whereby a shoulder 15 is formed, arranged to receive the upper terminal of the neck of a bottle 5.

It is to be understood that a number of gaskets 7 may be provided having central openings of different sizes to accommodate spigots of different dimensions. Likewise, if desired, a set of discharge tubes of different lengths may be provided in order to accommodate bottles of different lengths, it being desirable that the liquid should be discharged as near the bottom of the bottle as possible, in order to prevent undue beading.

In practical operation, the discharge tube 4 is thrust into the bottle, the upper terminal of the neck engaging the washer 12, and the annular rib 13 serving to close the neck of the bottle. The bottle 5 is retained against the resilient packing element by manual pressure, the bottle being tilted slightly from side to side or moved downward in order to provide for the escape of air from the bottle as it fills. By this arrangement it is possible to maintain the desired pressure within the bottle, and at the same time to provide for the escape of air therefrom when the pressure in the bottle becomes too great, without the use of valves or like complicated devices.

By flexing the neck 8, as hereinbefore described, the discharge tube 4 is made to clear the drip pan which is usually placed beneath bar spigots. For facility of illustration, I have shown the discharge tube 4 as extending to one side of the spigot, but it is obvious that since the device may readily be rotated upon the spigot, it may be arranged to project radially from the spigot at the side, front, or in any other desired position.

By mounting the gasket 7 as shown and by retaining it removably by the clamping ring 6, it is possible to reach the interior of the device without difficulty, whereby it may be thoroughly cleansed.

The resiliency of the washer 12 is increased by the addition of the washer 11, which is disposed between the said washer 12 and the flange 10. By thus duplicating the washers, the packing element may be more readily removed from the discharge tube than would be possible if it comprised an integral element. The washer 12 is subjected to more wear than is the washer 11, and when the

former becomes worn it may be replaced 25 without renewing the member 11.

Having thus described my invention, what I claim as new, and desire to protect by Letters Patent is:

A device of the class described comprising 30 a tubular attaching member arranged for rotatable mounting upon a cock, and being provided with a reduced, laterally flexed neck, internally threaded, the neck being provided at its lower end with an outwardly 35 extending flange; a discharge tube threaded to engage the neck and having a bore of equal diameter with the bore of the neck; a resilient packing element surrounding the discharge tube and having abutment with 40 the flange.

In testimony that I claim the foregoing as my own, I have hereto affixed my signature in the presence of two witnesses.

FRED W. DAFOE.
